UNITED STATES PATENT OFFICE.

FRANK CARTER AND EVERSHED CARTER, OF STAMFORD, ENGLAND, ASSIGNEES OF
ONE-THIRD TO GEORGE MILLS BLACKSTONE, OF STAMFORD, ENGLAND.

MEANS FOR STARTING AND REVERSING MULTIPLE-CYLINDER INTERNAL-COMBUSTION ENGINES.

1,361,681.

Specification of Letters Patent.

Patented Dec. 7, 1920.

Application filed January 5, 1920. Serial No. 349,513.

To all whom it may concern:

Be it known that we, FRANK CARTER and EVERSHED CARTER, subjects of the King of Great Britain, and both residing at Stamford, in the county of Lincoln, England, have invented new and useful Improved Means for Starting and Reversing Multiple-Cylinder Internal-Combustion Engines, of which the following is a specification.

10 Our invention relates to internal combustion engines of the four stroke cycle type, with three or more cylinders wherein the fuel is pumped in governed quantities for each charge and is sprayed by compressed air, and in which cam actuated air and exhaust valves are employed. The object of our invention is to provide means as hereinabove described for starting such an engine with compressed air from any position and, 20 if preferred, by duplicating the cams in either direction even when the starting air pressure is lower than that required for spraying the fuel into cylinders on half compression.

25 According to our invention we employ a single cam shaft and arrange in connection with it a number of levers appropriate for working the starting air valve, the working air inlet valve, the fuel spraying valve, and 30 the exhaust valve.

We arrange the cam shaft to slide, and to enable this to be done we form the cams with inclined ends in the usual well known manner. We also provide means whereby it 35 can be fixed in any one of four or seven axial positions, four for engines required to run in one direction only, and seven for engines running in either direction.

The accompanying drawings illustrate the 40 invention:-

Figure 1 is a side elevation of so much of a cam shaft as is necessary to operate the valves of one cylinder, showing the axial positions of the cam bowls, their angular 45 positions being ignored for the sake of clearness.

Fig. 2 is an end view of the cam shaft showing the angular positions of the air inlet, half compression, starting and working exhaust cams for one cylinder.

Fig. 3 is an end view showing the starting air and spraying cams.

Fig. 4 is a side elevation showing the end

of the cam shaft with the driving gear, and means for sliding the shaft axially.

55

Fig. 5 is an end elevation of the same.

Fig. 6 is a diagram showing the angular opening of the exhaust valve, when starting, with respect to the crank path.

Fig. 7 is a diagram showing the angular 60 opening of the working exhaust.

Figs. 8, 9, and 10 are diagrams showing the angular opening of the starting air valve, the working inlet air valve, and the fuel spray valve respectively.

65

a is the cam shaft, and *a'*, *a''* are bearings carrying the same and in which the shaft is slidably mounted; *b* is the exhaust valve cam bowl; *c* is the starter air cam bowl; *d* is the fuel sprayer valve cam bowl, and *e* 70 the working air inlet valve bowl.

The cam shaft is shown in the neutral position. For the sake of clearness, and to avoid overlapping, the seven positions of each bowl in respect to the cam shaft are indicated by dot and dash center lines. In the central or neutral position, the cam bowls are in the relative positions indicated by the dot and dash lines *f*, *g*, *h*, *i*, and no cams are under the bowls except the exhaust.

75

With the cam shaft in the first position to the right or left of the neutral according to the direction of running the bowls are in the relative positions indicated by 85 the lines *f'*, *f''*, *g'*, *g''*, *h'*, *h''* and *i'*, *i''*, and the starting air valve is operated by the cams *c'*, *c''*, or the cams *c²*, *c³*, every outstroke, and the exhaust valve during the whole of each in-stroke by the cam *b'*, or *b''*, and the 90 cam *b³*, or *b⁴*, the chamfered edge of the bowl riding on the sloping ends of these last mentioned cams.

In these positions no cams are under the working air inlet and fuel spraying valves, 95 and the engine is a single acting compressed air engine.

With the cam shaft in the second position to the right or left of neutral, the bowls are in the relative positions indicated by the 100 lines *f²*, *f⁵*, *g²*, *g⁵*, *h²*, *h⁵*, and *i²*, *i⁵* and the working air inlet valve is operated every alternate outstroke by the cam *c'*, or *c²*, the chamfered edge of the bowl riding on the 105 sloping end of the cam, the fuel spraying valve by the cam *d'*, or *d²*, at or near the

end of the compression stroke, and the exhaust valve by the cam b^3 , or b^4 , during each alternate in-stroke, and during the first portion of each compression stroke by the cam b^5 , or b^6 .

In these positions no cam is under the starting air bowl, and the engine works as a four stroke internal combustion engine on half compression.

- 10 With the cam shaft in the third position to the right or left of the neutral, the bowls are in the relative positions indicated by the dotted lines $f^3, f^6, g^3, g^6, h^3, h^6$, and i^3, i^6 , and the working air inlet valve is operated every 15 alternate out-stroke by the cam e' , or e^2 , the fuel spraying valve at or near the end of the compression stroke by the cam d' , or d^2 , and the exhaust valve every alternate in-stroke by the cam b^3 , or b^4 . In these 20 positions no cam is under the starting air bowl and the engine works as a four stroke cycle internal combustion engine on full compression.

In Fig. 2 the broken line n represents the 25 exhaust valve lever; o the air valve lever, and p their fulcrum. In Fig. 3 q is the starting valve lever, and q' its fulcrum, r the sprayer valve lever, and r' its fulcrum. The position of these levers can, of course, 30 be varied to suit the engine to which the invention is applied.

Referring now to Figs. 4 and 5, j is a lever on the plug j' , by means of which the cam shaft is moved axially through the eccentrically mounted member j^2 , engaging the slot k' , in the plunger k . This plunger is retained in a given angular position by the set pin k^2 , entering the keyway k^3 . The cam shaft a revolves in the plunger and is held 40 in position axially therewith by the shoulder a^2 , and nut a^3 .

The lever j is held in engagement with the notched plate j^3 , by means of a spring j^4 .

l is a long skew spur gear wheel fast on 45 the cam shaft a , and driven by the gear wheel l' , on the shaft l^2 .

The spiral angle of this gear is such that the opening faces of the exhaust cam for starting and working can be in the same 50 angular position, as shown at b^7, b^7 , Fig. 2, and yet cause the valve to open so much later in the starting position in order to avoid having the air starter and exhaust valves open at the same time.

55 In Figs. 6 to 10, the dotted circle m , represents the path of the crank pin, the small circles m' represent the points of opening of the several valves, and the small circles m^2 , the points of closing. The points m^3 are the inward dead centers and the dotted lines m^4 represent the angular lengths of opening of each valve.

In a three cylinder engine with the cranks at 120° , the air starter valves must be open 60 for more than 120° in order to insure a

start at any point. We find it the best practice to open the working exhaust at 45° before the outward dead center and to close it 15° past the inward dead center (see Fig. 7). Allowing 5° of lap we open the starter air 70 valve at 20° past the center m^3 , and keep it open for 130° so that if the starter exhaust be opened at the same period as the working exhaust the air and exhaust would be open together through an angle of 15° . 75

This is overcome by opening the starter exhaust at 25° before the outward dead center (Fig. 8) by means of the gear spiral as explained above, and the cams b^3, b^4 , are backed off at b^8, b^8 , to close the valve at the 80 same point as it closes in the working position.

To supply the compressed air for starting and spraying we provide an air compressor worked from the engine crank shaft and connect it with a container by means of a pipe having branches to the starting valves of the various cylinders. A separate pipe from the compressor leads to the spraying valves. 85

Should the container pressure be lower 90 than that required for spraying the fuel, a stop cock or the like is provided to disconnect the compressor from the starting valves and container to enable a sufficiently high pressure to be accumulated in the spraying 95 valve pipe to inject the fuel when the cam shaft is moved to the half compression position.

What we claim is:—

1. In an internal combustion engine of the 100 kind in which fuel is pumped in governed quantities for each charge, and injected at or near the end of the compression stroke, the combination of a starting air valve, a working air inlet valve, a fuel spraying 105 valve, and an exhaust valve, appropriate levers for working said valves, a single cam shaft provided with cams for actuating the valve levers, said cam shaft being slidable axially, means for sliding the cam shaft and retaining it in any one of four different axial positions, whereby the following results are obtained:— (1) neutral, engine at rest, (2) start as single acting compressed air engine, (3) work as four stroke cycle 110 internal combustion engine on half compression, and (4) work as four stroke cycle internal combustion engine on full compression 115 substantially as described.

2. In an internal combustion engine of 120 the kind in which fuel is pumped in governed quantities for each charge, and injected at or near the end of the compression stroke, the combination of a starting air valve, a working air inlet valve, a fuel 125 spraying valve, and an exhaust valve, appropriate levers for working said valves, a single cam shaft provided with duplicate cams on opposite sides of a neutral or central position for actuating the valve levers, 130

said cam shaft being slidable axially either way from a central position, means for sliding the cam shaft and retaining it in any one of three positions on either side of the central position, whereby the engine can be started and run in either direction, and the following results may be attained, (1) neutral, engine at rest, (2) start as single acting compressed air engine, (3) work as four-stroke cycle internal combustion engine on half compression, and (4) work as four-stroke cycle internal combustion engine on full compression.

3. In an internal combustion engine of the kind in which fuel is pumped in governed quantities for each charge, and injected at or near the end of the compression stroke, the combination of a starting air valve, a

working air inlet valve, a fuel spraying valve, and an exhaust valve, appropriate levers for working said valves, a single cam shaft provided with cams for actuating the valve levers, said cam shaft being slidable axially, means for sliding the cam shaft, a gear wheel, and a skew spur gear wheel fixed to the cam shaft and driven by said gear wheel, said skew spur gear wheel adapted, when the shaft is moved axially, to impart a twisting movement to the shaft to differentiate the opening positions of the exhaust cams for starting and working.
